UNITED STATES PATENT OFFICE.

SWAN J. LEVEEN, OF ROCK ISLAND, ILLINOIS, ASSIGNOR OF ONE-HALF TO CARL E. SHIELDS, OF ROCK ISLAND, ILLINOIS.

SOUND REPRODUCER FOR TALKING MACHINES.

Application filed April 7, 1920. Serial No. 371,983.

To all whom it may concern:

Be it known that I, SWAN J. LEVEEN, a citizen of the United States, residing at Rock Island, in the county of Rock Island and State of Illinois, have invented certain new and useful Improvements in Sound Reproducers for Talking Machines, of which the following is a specification.

My invention relates to sound reproducers for talking machines, and embodies certain novel features whereby the tones of the instrument can be greatly modulated, and the volume thereof reduced, without in any way interfering with the clearness and distinctness of the tones.

Most machines of the kind mentioned are provided with some means for modifying the volume of the sound produced thereby. This usually consists of some form of shutters or dampers which are projected into or across the horn-shaped passage through which the sound travels. These contrivances always obstruct the passage to a greater or less extent, and interfere with the passage of a portion of the sound waves. These sound waves are thus turned, or refracted, toward the diaphragm, and hinder the free movement of the other sound waves, destroying the clearness of the tones, and giving a muffled effect thereto.

One of the principal objects of the present invention is to overcome this fault. This is accomplished by means of devices which do not in any way interrupt nor interfere with the passage of the sound-waves through the horn or sound intensifying chamber of the machine, but which are on the opposite side of the diaphragm therefrom, and control the action of the diaphragm itself.

The construction, arrangement and operation of the various parts of my invention will be more fully understood from the following specification, reference being had to the drawings accompanying the same, in which:

Fig. 1 shows my invention in front elevation, detached.

Fig. 2 is a vertical cross-section thereof.

1 represents the reproducer box, provided with a connection collar 2, within which box is supported the usual diaphragm 3. The box 1 has an extension 4, in which is held a circular plate 5, the edge of said plate having a screw connection with the part 4, so that such plate can be adjusted with

relation to the diaphragm. 6 is a needle-arm, passing through a central opening in the plate 5 and attached to the diaphragm at one of its ends, and connected at its other end with a needle-bar 7, rockingly mounted 60 between projections 8 on the box 1.

The plate 5 can be rotated by means of a handle 9, having a perforation which engages a pin 10 fixed in the plate 5. Said arm is projected into an arm 11 which has 65 a bearing on the plate 4 at the opposite side thereof, said arm having a bearing at a central point against a disk 12, secured to the plate 5, and perforated to permit the passage of the arm 6. The arm 9 with its 70 extension 11 exerts a spring tension upon the disk 12, tending to hold the same outwardly, and preventing any vibration of the plate 5 which might be imparted thereto from the diaphragm.

The inner face of the plate 5 is slightly concaved, and is provided with a lining 13 of fabric or other suitable material, which presents to the diaphragm a roughened face or surface. As is well understood, the vibrations of the diaphragm cause the sounds to be imparted equally on each side thereof. If the lining 13 were not used the sounds moving outwardly from the diaphragm would strike against the plate 5, 85 and be refracted, returning against the diaphragm, and causing a counter-sound through the diaphragm, tending to confuse the tones on the inner side thereof. The roughened face of the lining 13, however, 90 absorbs the tones moving outwardly, and prevents them from interfering with the clear tones of the diaphragm which are passing through the horn of the machine.

As before mentioned, in some machines it 95 has been customary to undertake to reduce the volume of the tones by means of obstructions in the passage-way for such tones, but the same result can be produced by limiting or reducing the vibrating power of 100 the diaphragm. This is accomplished in the present invention by adjustment of the plate 5 towards the diaphragm, and is caused primarily by the consequent reduction of the air cushion between the plate 105 and diaphragm. This air cushion possesses a greater or less amount of elasticity, depending upon the thickness of the space between the plate and diaphragm, the resistance of such cushion to the vibrations of 110

the diaphragm increasing as the plate approaches the latter. This tends to limit the vibrations, changing the quality of the tone, and reducing the volume thereof to some extent. As the movement of the plate 5 inwardly continues, however, the outer circle of the lining 13 comes in contact with the diaphragm, in effect reducing the circumference thereof, and still further limiting the vibrations. This also operates to reduce the volume of the tones on the inner side of the diaphragm. The amount of contact of the lining 13 with the diaphragm can be gradually increased, until a very limited portion of such diaphragm is permitted to vibrate, reducing its tone imparting power proportionately.

The action of the lining 13 upon the diaphragm has a tendency to increase the pitch 20 of the tones, which would be refracted from the plate 5, and interfere with the tones on the opposite side of the diaphragm, if it were not for the presence of such lining, the roughened surface of which absorbs the 25 sharp tones on the outer side of said diaphragm. The clearness and distinctness of the reduced tones is thereby retained.

The plate 5 also interferes with the tones on the outer side of the diaphragm escaping 30 into the outer atmosphere, so as to interfere with and confuse the sounds produced from the inner side of such dia-

phragm. On this account the use of a cover or other means for enclosing the reproducer is not necessary, so far as these tones are concerned.

It will be obvious that when it is desired to increase the volume once more, this can be done by moving the plate 5 outwardly again.

There has been shown in the drawings and set forth in the specification herein the preferred form of the invention, and it is obvious that changes can be made in the construction and arrangement thereof 45 without departing from the spirit of the invention.

What I claim and desire to secure, is:

In a device of the class described, the combination of a reproducer box and diaphragm mounted therein; a plate supported in said box by a screw-threaded connection, so as to be capable of adjustment with relation to said diaphragm, and having a concave face adjacent to said diaphragm; a lining on said concave face capable of modifying the vibratory tones of the diaphragm; and means for rotating said plate, and exerting a tension thereon to prevent vibration thereof.

In testimony whereof I affix my signature.

SWAN J. LEVEEN.
